European Community Design Registration No. 002573469-0001, issued Nov. 7, 2014.

Primary Examiner — Brian N Vinson*(74) Attorney, Agent, or Firm* — Fish & Tsang LLP(57) **CLAIM**

The ornamental design for an electric pillar candle, as shown and described.

DESCRIPTION

FIG. 1 is a perspective view of an electric pillar candle showing my new design.

FIG. 2 is a rear view thereof.

FIG. 3 is a front view thereof.

FIG. 4 is a left side view thereof.

FIG. 5 is a right side view thereof.

FIG. 6 is a top view thereof; and,

FIG. 7 is a bottom view thereof.

The broken line disclosure represents portions of the light which form no part of the claimed design.
